MILKING MACHINE PULSATORE

Sam P. Wall, Chicago, Ill., assignor to Rite-Way
Products Company, Chicago, Ill., a corporation
of Delaware

Application December 22, 1945, Serial No. 636,860

9 Claims. (Cl. 31—61)

1

This invention relates to milking machine pulsators, particularly to pulsators of the type which operate to apply suction and atmospheric pressure alternately to the teat cups of a milking machine. More specifically, the invention relates to a pulsator of the type wherein the change from suction to atmospheric pressure is brought about by the reciprocation of an operating piston and wherein the frequency of the reciprocation of the piston is determined by a second piston, referred to as a timing piston, whose speed is adjustable.

It is one of the objects of the present invention to provide a pulsator of the above mentioned type wherein the piston cylinders are formed in a central block in aligned pairs and wherein the pistons in an aligned pair of cylinders are interconnected by means of a bar which is entirely outside of the cylinders and therefore does not require any packing. It is a further object of the present invention to provide a vacuum operated pulsator having few parts and wherein the ports are all located in a single block which is the block in which the cylinders are formed. It is a still further object of the present invention to provide a pulsator of the above mentioned character which is simple and economical of construction and wherein the number of parts that may get out of order or result in leakage are reduced to a minimum.

The attainment of the above and further objects of the present invention will be apparent from the following specification taken in conjunction with the accompanying drawings forming a part thereof.

In the drawings:

Figure 1 is a plan view of a pulsator embodying the present invention;

Figure 2 is a side view of the pulsator of Figure 1;

Figure 3 is a half section end view of the pulsator taken along the line 3—3 of Figure 1;

Figure 4 is a top view of the pulsator of Figure 1 with the draw bars and pistons and valves removed;

Figure 5 is a side view of the structure of Figure 4;

Figure 6 is a bottom view of the structure of Figure 4;

Figure 7 is a sectional view taken along the line 7—7 of Figure 1; and

Figure 8 is a sectional view through the end of one of the pistons, said view being taken along the line 8—8 of Figure 3.

Reference may now be had more particularly to ports 38 and 39 extend downwardly and then

to the drawings wherein like reference numerals designate like parts throughout.

The pulsator of the present invention, indicated in general by the reference numeral 1, includes a central cylinder block 2 which has four cylinder bores 3, 4, 5 and 6 formed therein at the opposite sides 7—7' thereof. Each cylinder bore extends from one face of the block into the block a distance almost but not quite to the center of the block, as may be seen from Figure 3 and Figure 4. This leaves a central wall 10 between the cylinder bores 3—4 and between the bores of the cylinders 5—6. The central wall 10 has a vacuum port 11 extending entirely through the block. Adjacent the port 11 there are two ports 12—13 which open at the top 14 of the cylinder block and extend vertically downwardly into the cylinder block into communication with horizontal ports 15—16, respectively. Short nipples 17—18 thread into the end 19 of the cylinder block and establish communication with the ports 15—16, respectively. These nipples are provided for receiving rubber hose connections that extend to the outer shell of the inflations of the usual teat cups.

At the bottom of the pulsator there is secured a fitting 22 in any desired manner, as by means of a pair of screws 23. This fitting includes a smooth outer cylindrical tube 24 having a flange 25 at the top. The tube 24 is adapted to fit into a similarly shaped opening in a milk bucket, although this is optional. The cylindrical wall of the tube 24 has a nipple 26 extending thereinto. This nipple is adapted to receive the end of a hose leading to a vacuum pump or a vacuum line. The flange 25 has an opening in line with the port 11. The central wall 10 has a vacuum port 30 which extends from the top surface of the cylinder block 2 through the block and through the flange 25 and opens at the bottom on the interior of the tubular portion 24. This port is intersected off center by a threaded port 31 in which is threaded an adjusting screw 32 that extends through the end 33 of the pulsator block 2. The port 31 communicates with a vertical port 34 that also opens at the top of the cylinder block. Two additional ports 35 and 36 extend from the top of the cylinder block to the cylinder bores 5 and 6, respectively, the openings of the ports 34—35—36 at the top of the valve block being in alignment. Two additional ports 38 and 39, which open on the top of the block on opposite sides of the port 30, extend to the cylinder bores 4 and 3, respectively. To that effect the

meet with intersecting diagonal ports 40 and 41, respectively.

Four similar pistons slide in the cylinder bores 3, 4, 5 and 6. The pistons are indicated by the reference numerals 45. Each piston has a cylindrical bore 46 therein at the back portion thereof and at the front has a conventional cup-shaped sealing gasket 47 of leather or the like, held in place by a disc 48 and a screw 49. A pair of bridge members 50 and 51 are provided. Each bridge member includes a cross bar from which extend a pair of pin-like fingers 54—54 each of which extends into the bore 46 in the adjacent piston. Each piston is slotted at its back side, as indicated at 56, for receiving a spring 57 which presses against the finger 54 to hold the same frictionally against retraction from the piston. Each bridge 50—51 extends across the top of the block 2. The bridge 50 has secured thereto a slidable valve 60 which slides on the top surface of the block 2. The valve 60 has on the under surface thereof passageways 61—62 which open to atmosphere, and has also on the under side thereof a Z-shaped passageway 63 that is adapted to establish connections between the port 30 and the ports 38—39, selectively. When either one of the last mentioned ports is connected to the central vacuum port 30 the other one of the two ports 38—39 is connected to atmosphere by the port 61 or the port 62, as the case may be. The bridge 51 is connected to a valve plate 70 which also slides on the top surface of the cylinder block. The under surface of the valve plate 70 has a passageway 71 which is adapted to connect the vacuum port 34 with the vacuum port 35 or 36, selectively. The under surface of the valve plate 70 also has passageways 72—73 that lead to atmosphere and are adapted to connect with the ports 36 or 35, respectively. When the passageway 71 connects the port 36 with the port 34 the passageway 73 connects the port 35 with atmosphere, as may be seen from Figure 1. When the valve plate 70 is moved to its alternate position the passageway 72 connects the port 36 to atmosphere, and the passageway 71 in the plate 70 connects the port 36 to the vacuum port 34.

In addition to the above mentioned passageways the plate 70 has holes 76 and 77 extending therethrough to the atmosphere. In addition the under side of the plate 70 has a tortuous passageway 78 formed therein. When the valve plate is in the position illustrated in Figure 1 the passageway 78 connects the vacuum port 11 with the port 12. At the same time the passageway 77 overlies the port 13. When the bridge 51 is in its opposite extreme position the opening 76 overlies the port 12, and the tortuous passageway 78 on the under side of the valve plate 70 establishes communication between the port 13 and the vacuum port 11.

An explanation will now be given of the mode of operation of the pulsator thus far described. Assume that the sets of pistons are in their opposite positions, as illustrated in Figure 1. At that time atmospheric pressure is applied to the nipple 18 by way of the opening 77, and vacuum is applied to the port 12 and nipple 17 by way of the vacuum port 11, through the tortuous passageway 78 on the under side of the valve plate 70. Vacuum is thus applied to the shells of one of the two sets of teat cups, and atmospheric pressure is applied to the shells of the other of the two sets of teat cups which are connected to the respective nipples 17—18. At the same time vacuum is applied by way of the port 30 to the

port 38, thence by way of the port 40 to the operating face of the piston in the cylinder 4, and atmospheric pressure is applied by way of the port 39 and passageway 41 to the operating face of the opposite piston within the cylinder bore 3. This immediately causes pistons which are interconnected by the bridge 51 to move from the position illustrated in Figure 1 to their alternate position, thereby immediately changing the vacuum and atmospheric connections to the nipples 17—18. As soon as the bridge 51 reaches its alternate position the passageway 71 on the under side of the valve plate 70 establishes vacuum connections from the port 34 to the port 35, and the passageway 72 on the under side of the plate 70 establishes atmospheric connections to the port 36. Atmospheric pressure is thus applied to the working face of the piston in the cylinder 6 and vacuum pressure is applied to the working face in the cylinder 5. This immediately causes the two control pistons that are interconnected by the bridge 50 to commence moving from the positions illustrated in Figure 1 to their alternate positions. The rate of movement is controlled by the rate at which air can move through the port 34, as determined by the setting of the screw 32. The pistons connected by the bridge 50 move slowly until they reach the position opposite to that illustrated in Figure 1. In that position the Z-shaped passageway 63 in the bottom surface of the valve block 60 establishes communication from the vacuum port 30 to the port 39, and the passageway 61 establishes atmospheric connections to the port 38. This causes the operating pistons that are connected by the bridge 51 immediately to return to the position illustrated in Figure 1. It is thus apparent that the timing pistons which are the pistons connected to the bridge 50 move back and forth slowly at a rate of speed determined by the setting of the adjusting screw 32, and whenever they reach one extreme position or the other they establish vacuum and atmospheric connections for reversing the position of the operating pistons, which are the pistons that are interconnected by the bridge 51. The operating pistons immediately move to their opposite position and when they reach that position the valve plate 70 reverses the vacuum and atmospheric connections to the cylinders of the timing pistons and thus causes the cycle to be repeated.

In compliance with the requirements of the patent statutes I have here shown and described a preferred embodiment of my invention. It is, however, to be understood that the invention is not limited to the precise construction here shown, the same being merely illustrative of the principles of the invention. What I consider new and desire to secure by Letters Patent is:

1. A pulsator for milking apparatus, comprising a valve block having an upper surface and two oppositely disposed side surfaces and two oppositely disposed end surfaces, two parallel cylinder bores extending inwardly from each of said side surfaces of the block and with the cylinder bores in oppositely aligned pairs, the block including an imperforate closure between cylinders of each pair to close them off from one another, a piston in each cylinder, one end of each piston facing into the cylinder and the opposite end being in the open atmosphere, piston rods joining together the pistons in the oppositely disposed cylinders adjacent their ends that are in the open atmosphere, said piston rods extending across the upper flat surface of the valve block.

2. A pulsator for milking apparatus, comprising a valve block having an upper surface and two oppositely disposed side surfaces and two oppositely disposed end surfaces, two parallel cylinder bores extending inwardly from each of said side surfaces of the block and with the cylinder bores in oppositely aligned pairs, a piston in each cylinder, piston rods joining together the pistons in the oppositely disposed cylinders, said piston rods extending across the upper flat surface of the valve block, air passageways each opening at one end in one of the cylinders and the other ends of the respective passageways terminating in ports at the upper surface of the valve block with the ports of each pair of air passageways from oppositely disposed cylinders located in pairs adjacent the piston rod of the other pair of oppositely disposed cylinders, a vacuum passage in said valve block, air passageways extending from said vacuum passage to ports at the upper surface of said valve block adjacent the respective pairs of ports, and valve means at the upper surface of the valve block for connecting each of the first mentioned ports to a port from the vacuum passage and then exposing said first mentioned port to the atmosphere, thereby producing alterations of the pressure in the cylinder bores and resulting movement of the pistons therein.

3. A pulsator for milking apparatus comprising a valve block having an upper surface and two oppositely disposed side surfaces, two sets of aligned cylinder bores formed in the block and opening in said side surfaces, the combined axial length of each of the bores of a set being substantially less than the width of the block so as to leave a mass of the block material between aligned bores which mass constitutes the closure for adjacent ends of aligned bores, pistons reciprocable in the respective bores, bridging means connecting the pistons in aligned bores, said bridging means extending across the upper surface of the block, ports in the portion of the block between aligned cylinder bores and terminating at the upper surface of the block, and valves sliding on the upper surface of the block and controlling the ports, said valves being connected to and operated by the respective bridging means.

4. A pulsator for milking apparatus, comprising a valve block, two incommunicating cylinder bores extending inwardly from each of two opposite sides of the block and opening outwardly of the block, the corresponding bores in the opposite sides of the block being in alignment, operating pistons in one set of aligned bores and timing pistons in the other set of aligned cylinder bores, means for interconnecting aligned pistons comprising bridging members extending across the block, air passageways for the cylinder bores terminating in ports at the top of the block between the bores therein, valve means operated by the timing pistons for controlling the establishment of vacuum connections alternately to the respective ports leading to the cylinders having the operating pistons therein, a vacuum passageway, valve means operated by the operating pistons for connecting the vacuum passageway alternately to the respective ports leading to the cylinders having the timing pistons therein, and air flow regulating means in said vacuum passageway.

5. A pulsator for milking apparatus, comprising a valve block, two incommunicating cylinder bores extending inwardly from each of two opposite sides of the block and opening outwardly

of the block, the corresponding bores in the opposite sides of the block being in alignment, operating pistons in one set of aligned bores and timing pistons in the other set of aligned cylinder bores, means for interconnecting aligned pistons comprising bridging members extending across the block and fingers extending from each bridging member and slidable into aligned pistons and releasable spring means releasably holding the fingers and pistons together, air passageways for the cylinder bores terminating in ports at the top of the block between the bores therein, valve means operated by the timing pistons for controlling the establishment of vacuum connections alternately to the respective ports leading to the cylinders having the operating pistons therein, a vacuum passageway, valve means operated by the operating pistons for connecting the vacuum passageway alternately to the respective ports leading to the cylinders having the timing pistons therein, and air flow regulating means in said vacuum passageway.

6. A pulsator for milking apparatus, comprising a valve block having an upper surface and two oppositely disposed side surfaces and two oppositely disposed end surfaces, two parallel cylinder bores extending inwardly from each of said side surfaces of the block and with the cylinder bores in oppositely aligned pairs, a piston in each cylinder, piston rods joining together the pistons in the oppositely disposed cylinders, each piston rod including a crossbar that extends across the upper flat surface of the valve block and at the ends of said bar there being depending fingers that extend into the respective pistons.

7. A pulsator for milking apparatus, comprising a valve block having an upper surface and two oppositely disposed side surfaces and two oppositely disposed end surfaces, two parallel cylinder bores extending inwardly from each of said side surfaces of the block and with the cylinder bores in oppositely aligned pairs, a piston in each cylinder, piston rods joining together the pistons in the oppositely disposed cylinders, each piston rod including a crossbar that extends across the upper flat surface of the valve block and at the ends of said bar there being depending fingers that extend into the respective pistons, each of said fingers being at right angles to the longitudinal axis of the piston into which it extends and being slidable with respect to its piston so that the fingers may be retracted from the pistons by a retractive movement of the crossbar thereby releasing the pistons for removal from the cylinders.

8. A pulsator for milking apparatus, comprising a valve block having an upper surface and two oppositely disposed side surfaces and two oppositely disposed end surfaces, two parallel cylinder bores extending inwardly from each of said side surfaces of the block and with the cylinder bores in oppositely aligned pairs, a piston in each cylinder, piston rods joining together the pistons in the oppositely disposed cylinders, each piston rod including a crossbar that extends across the upper flat surface of the valve block and at the ends of said bar there being depending fingers that extend into the respective pistons, each of said fingers being at right angles to the longitudinal axis of the piston into which it extends and being slidable with respect to its piston so that the fingers may be retracted from the pistons by a retractive movement of the crossbar thereby releasing the pistons for removal from the cylinders, and releasable spring means

releasably holding the fingers against retraction from their respective cylinders.

9. A pulsator for milking apparatus, comprising a valve block having an upper surface and two oppositely disposed side surfaces and two oppositely disposed end surfaces, two parallel cylinder bores extending inwardly from each of said side surfaces of the block and with the cylinder bores in oppositely aligned pairs, a piston in each cylinder, piston rods joining together the pistons in the oppositely disposed cylinders, each piston rod including a crossbar that extends across the upper flat surface of the valve block and at the ends of said bar there being depending fingers that extend into the respective pistons, each of said fingers being at right angles to the longitudinal axis of the piston into which it ex-

tends and the pistons being rotatable about the fingers about an axis at right angles to the longitudinal axis of the piston.
